UNITED STATES PATENT OFFICE

141,602

DESIGN FOR AN AVIATOR'S OXYGEN MASK OR SIMILAR ARTICLE

Arthur H. Bulbulian, Rochester, Minn.

Application July 26, 1944, Serial No. 114,568

Term of patent 14 years

(Cl. D83—1)

To all whom it may concern:

Be it known that I, Arthur H. Bulbulian, a citizen of the United States, residing at Rochester, in the county of Olmstead and State of Minnesota, have invented a new, original, and ornamental Design for an Aviator's Oxygen Mask or Similar Article, of which the following is a specification.

Reference being had to the accompanying drawings, forming part of the specification.

Fig. 1 is a front elevational view of an aviator's oxygen mask or similar article viewed from the

outside thereof, showing my new design.

Fig. 2 is a side view of the mask shown in Fig. 1.

Fig. 3 is a top plan view of the mask viewed from the front or nose-receiving portion thereof.

Fig. 4 is a rear elevational view of the mask viewed toward the inside thereof.

I claim:

The ornamental design for an aviator's oxygen mask or similar article, substantially as shown.

ARTHUR H. BULBULIAN.
